DOME LIGHT

Herbert J. Graham, Philadelphia, Pa., assignor
to Electric Service Supplies Company, Philadelphia, Pa., a corporation of Pennsylvania

Application August 24, 1933, Serial No. 686,485

5 Claims. (Cl. 240—7.35)

This invention relates generally to illuminating fixtures and more particularly to improvements in vehicle dome or ceiling lighting units.

It is among the principal objects of the present invention to provide a new and improved vehicle dome light which is not only simple in construction and inexpensive to manufacture but which is also compact in design and of pleasing external appearance.

10 Another object of the present invention is the provision in a dome light having a lamp supporting body and a dome or globe operatively associated therewith of means for facilitating the disengagement of said dome or globe from the body, said means serving normally to provide a substantial and efficient hinged connection between said lamp supporting body and said globe.

Still further objects of the invention are to provide a substantially weather tight connection 20 between the hinged elements of the lighting unit when the latter are secured together in operative relation and to provide effective means for retaining the globe in position against accidental displacement when the same is open with respect 25 to the lamp supporting body or entirely removed therefrom.

Other objects of the invention and advantages thereof resulting from the details of construction will be apparent more fully hereinafter.

30 The invention consists substantially in the combination, construction, location and relative arrangement of parts, all as will appear more fully hereinafter, as shown in the accompanying drawing and as finally pointed out in the appended 35 claims.

In the said accompanying drawing:—

Figure 1 is a front plan view of a dome light constructed in accordance with and embodying the principles of the present invention;

40 Figure 2 is a rear plan view of the dome light;

Figure 3 is a side elevational view of the dome light showing the cover assembly thereof in hinged relation to the lamp supporting body thereof;

45 Figure 4 is a view similar to Figure 3 but showing the cover assembly entirely removed from the lamp supporting body;

Figure 5 is a vertical sectional view of the dome light; and

50 Figure 6 is a perspective view of the hinge element.

Referring now more particularly to the drawing it will be seen that the dome light, designated generally by the reference numeral 10, comprises 55 a main body or base 11 the central portion 12 of

which is dished or shaped to form a concave reflecting surface 13. This central portion 12 is provided with a circumferentially extending, plane marginal surface 14 the outer edge of which is turned upwardly to provide a substantially axially extending annular rim portion 15 terminating in a laterally extending flange 16. As appears most clearly in Figure 5, this flange 16 which forms an integral part of and extends circumferentially around the rim 15, is inclined 5 with respect to the horizontal plane of the outer free edge thereof.

The flange 16 is provided with a plurality of apertures 17 through which securing elements, preferably in the form of screws 18, are projected for securing the body 11 to the ceiling of the vehicle or to any other desired supporting surface for the lighting unit. Encircling the rim 15 of the body 11 is a gasket 19 of cork or other suitable resilient material. This gasket is preferably secured more or less permanently to the rim 15 by any suitable means. In the instance shown, the rim 15 is provided with a plurality of circumferentially spaced struck-out elements 20 of substantially triangular form, the sharpened ends of 25 these elements being adapted to be embedded in the gasket 19. Suitably secured to the central portion 12 of the body 11 is a lamp socket 21 for supporting a lamp bulb 22.

Adapted for operative association with the lamp 30 supporting body 11 is a closure assembly comprising a globe support 23 which is centrally apertured to permit the projection therethrough of a glass globe or dome 24. As appears most clearly in Figure 5, the peripheral edge of the member 23 35 is rolled, as at 25, to provide a beaded edge within which is received a spring wire dome retaining element 26, this element being provided at circumferentially spaced intervals with inwardly directed portions 27 adapted to overlie the inner 40 edge of the dome 24 whereby to retain the latter in position within its supporting member 23. It will be observed that the rolled edge 25 of the dome supporting member 23 is of a diameter sufficient to permit it to circumferentially engage the 45 free marginal edge of the lamp supporting body 11. It will further be observed that when the lamp supporting body and the closure assembly are assembled in the relation shown in Figure 5, the inner surface of the dome 24 immediately adjacent the free edge thereof is brought into intimate engagement with the cushioning gasket 19 thereby affording at this point a substantially weather-tight seal for protecting the interior of 50 the lighting unit against the deleterious influences 55

of moisture, dust and the like, the gasket 19 further serving to effectually preclude any rattling or play between the several parts of the lighting unit.

5. Located at one point in the rolled edge 25 of the dome supporting member 23 is a relatively fixed pin 28 to which is hingedly secured a freely extending leaf 29. This leaf 29, which is of substantially rectangular shape, is preferably constructed of spring metal, the central and outer portions thereof being oppositely bent slightly with respect to the plane of the inner hinged portion thereof. The lamp supporting body 11 is provided in the flanged portion 16 thereof with 15 a pair of radially spaced struck-out strap portions 30 and 31 to afford a plurality of radially spaced slots 32 in said flange 16 through which the free end of the leaf 29 may be projected. Due to the springy nature of this leaf member and 20 to its longitudinal cross-sectional shape, when said leaf member is projected through the slots in the portion 16 of the lamp supporting body 11, a quick-detachable connection is afforded which is sufficient to maintain the lamp supporting body 25 11 and the dome supporting member 23 in the assembled relation shown in Figure 3, it being observed that the closure assembly is thus hingedly secured to the lamp supporting body 11, which latter is in turn fixedly secured to the wall 30 or ceiling of the vehicle.

In order to effect a sufficiently positive interlock between the leaf 29 and the lamp supporting body 11, it will be observed that the outer struck-out portion 30 is so formed as to provide a shoulder 33 with which the bend 34 in the leaf 29 is 35 adapted to engage (see Figure 5). In addition it is preferable that the leaf 29 be so formed that when it is fully inserted in position the outer bend 35 thereof is in position to frictionally engage 40 the edge 36 of the struck-out portion 31.

In order to secure the closure assembly in the closed relation shown in Figure 5, a nut and bolt arrangement is provided at a point diametrically opposite the hinged connection. A nut 37 is secured to the rear surface of the flange 16 and in registry with an aperture 38 formed in said flange. The globe support 23 is also provided with an aperture 39 through which is projected a headed bolt 40 for threaded engagement with the nut 37. Any suitable means may be employed for preventing axial displacement of the bolt relatively to the support 23, it being understood that upon threading the bolt into the nut, the dome support 23 and the dome carried thereby will be rotated about the hinged connection and so drawn 55 into the position shown in Figure 5.

If, for any purpose, it becomes desirable to remove the dome cover assembly bodily from the lamp supporting body, it is merely necessary to 60 swing the said assembly into the full line position shown in Figure 3 and then, by a lateral movement, shift the assembly so as to effect the disengagement of the leaf 29 from the lamp supporting body 11. It will be understood of course that 65 the invention is susceptible of various changes and modifications without departing from the general principles thereof.

What is claimed as new and useful is:—

1. In a dome light, a support shaped to form a

reflect and having a lamp socket operatively associated therewith, said support including a circumferentially extending flange encircling the reflector portion thereof, a centrally apertured plate, a member in the form of a leaf having one end thereof hingedly secured to the peripheral edge of said plate, slotted means in said circumferentially extending flange for slidably receiving the freely extending portion of said leaf member, and a dome centrally received within 10 said apertured plate.

2. In a dome light, a support shaped to form a reflector and having a lamp socket operatively associated therewith, said support being provided with a circumferentially extending flange, a dome assembly adapted to embrace and cover the reflector portion of said support, said assembly including a plate the peripheral edge of which is adapted to overlie and engage the peripheral edge of said flange, a leaf member having one end thereof hingedly secured to said peripheral edge of said plate, and slotted means in said flange for frictionally receiving and retaining in position the freely extending body portion of said leaf member.

3. In a dome light, a support shaped to form a reflector and having a lamp socket operatively associated therewith, a dome assembly adapted to embrace and cover the reflector portion of said support, a leaf member hingedly secured to and adapted to extend radially inwardly of the edge of said assembly, and slotted means in said support for frictionally receiving the freely extending body of said leaf member.

4. In a dome light, a base member shaped to form a reflector having a lamp socket operatively associated therewith, said base member having a plane marginal portion surrounding said reflector, said marginal portion having formed therein a plurality of radially spaced slots, a leaf member the body of which is threaded through said slots for frictional retention therein, the outer end of said leaf member projecting beyond the peripheral edge of said marginal portion, and a dome assembly hinged to said projecting end of the leaf member and adapted to embrace and cover the reflector portion of the base member.

5. A dome light, a support having a plane marginal portion and a raised central portion, said central portion being dished to form a reflector, a dome assembly including a glass dome and a retainer therefor, the overall diameter of said retainer being approximately equal to that of said base member, a leaf member hinged to the peripheral edge of said retainer and adapted to project radially inwardly thereof, and slotted means in said marginal portion of the base member for frictionally receiving and retaining the freely extending body of said leaf member, said leaf member being operative when secured to said base member to permit the dome assembly to be freely swung into open or closed position and being further adapted to be withdrawn laterally from said slotted means whereby to effect the separation of said dome assembly bodily from said support.

HERBERT J. GRAHAM.
